United States Patent Office.

ERASTUS BUCK, OF VINCENNES, INDIANA.

Letters Patent No. 79,443, dated June 30, 1868.

IMPROVEMENT IN BELT-SHIPPERS.

The Schedule referred to in these Letters Patent and making part of the same.

TO ALL WHOM IT MAY CONCERN:

Be it known that I, ERASTUS BUCK, of Vincennes, in the county of Knox, and State of Indiana, have invented certain new and useful Improvements in Belt-Shippers; and I do hereby declare that the following is a full, clear, and exact description thereof, reference being had to the accompanying drawings, and to the letters of reference marked theron, which form a part of this specification, in which—

Figure 1 represents a plan or top view of a series of pulleys and belts, with my improvement applied thereto.

Figure 2, a plan or top view of the same, and

Figure 3 a view of the shipper detached.

The object of my invention is to provide a convenient device for shipping belts, by the use of which the wear and rattling of the loose pulley upon the shaft will be obviated, and the belt pressed towards the surface of the pulley in the operation, instead of being lifted from it; as is ordinarily the case; to which end my improvements consist in mounting the loose pulley of the primary shaft, from which power is to be communicated, upon a stationary sleeve, which encircles the said shaft, so as to prevent wear or rattling of the loose pulley upon the shaft, when the belt is shifted to the fixed pulley, and providing the shipper, which shifts the belt, with inclined arms furnished with friction-rollers, together with a projection, which actuates a pivoted lever, by means of which the loose pulley is pressed against the fixed one, while the belt is being shifted.

In the accompanying drawings, which show a convenient arrangement of parts for carrying out the objects of my invention, A represents the shaft of the prime mover, which is rotated by the crank A', and B the main or line-shaft, from which power is to be communicated to a counter-shaft, F. The main shaft C is provided with a pulley, C', which carries a belt, B', passing around a pulley, B, on the shaft A, from which it is driven. The shaft C passes through a sleeve, D, secured to the beam K', upon which sleeve a loose pulley, D', is mounted. A fixed pulley, E, is secured upon the shaft C, adjoining the loose pulley D', over which a belt, E', passes, to drive the counter-shaft F, by means of a fixed pulley, F', secured upon it. The counter-shaft F likewise carries a loose pulley, F'. The belt E' is shifted from the fast to the loose pulleys, and, *vice versa*, by means of the shipper H, which slides in the beams K K', in which the shafts have their bearings. The shipper H is provided with arms I, between which the belt E passes, and by which it is shifted. The arms I have friction-rollers I' upon them, and are set at an angle, converging towards each other, when the shipper passes within the belts, or diverging when it is without. By this arrangement of the arms, the belt is pressed towards the surface of the pulley when shifted, instead of being drawn from it, as is ordinarily the case. A bent lever, G, is pivoted to the beam K', one end of which is forked, to partially embrace the sleeve D adjacent to the loose pulley D'. A projection, h, upon the side of the shipper H, bears against the opposite end of the lever G, and thereby presses the pulley D' against the pulley E, when the belt is shifted from the former to the latter.

When the shipper is moved, to transfer the belt from the loose to the fast pulleys, the projection h, striking against the end of the lever G, causes its opposite end to press the loose pulley D' against the pulley E, the friction thereby produced causing the pulley D' to revolve until the belt has passed from it, when it remains stationary upon the sleeve D, and wear or rattling is obviated. The inclined position of the arms I causes the belt to be pressed up to the surface of the pulley while being shifted.

What I claim, and desire to secure by Letters Patent, is—

The combination of the shipper H, pivoted lever G, and pulleys D' E, when arranged and operating substantially as described.

In testimony that I claim the foregoing as my own, I affix my signature in presence of two witnesses.

ERASTUS BUCK.

Witnesses:

H. A. BUCK,

JAMES S. MAYES.
